UNITED STATES PATENT OFFICE.

RICHARD SCHOFIELD, OF PARIS, CANADA, ASSIGNOR OF SEVEN-TWELFTHS
TO JOHN PENMAN, OF SAME PLACE.

CLOTH-CUTTING MACHINE.

SPECIFICATION forming part of Letters Patent No. 451,335, dated April 28, 1891.

Application filed September 25, 1890. Serial No. 366,113. (No model.)

To all whom it may concern:

Be it known that I, RICHARD SCHOFIELD, 5
mechanic, of the town of Paris, in the county of
Brant, in the Province of Ontario, Canada,
have invented a certain new and useful Im-
provement in a Machine for Cutting Cloth, of
which the following is a specification.

My invention relates to an improvement in
a machine for cutting cloth, patented by me in
10 the United States of America on April 2, 1889,
under No. 400,603, and in Canada on Novem-
ber 14, 1889, under No. 32,824; and it consists
in the peculiar construction, arrangement,
and combinations of parts hereinafter more
15 particularly described and then definitely
claimed.

Figure 1 is a view showing my improved
cloth-cutter in operation. Fig. 2 is an enlarged
20 perspective view of my improved cloth-cutter,
a portion of the casing being broken away to
expose the interior construction of the ma-
chine. Fig. 3 is a cross-sectional detail show-
ing the connection between the spindle of the
25 flexible shaft with the gearing for propelling
the cutter.

A represents the spindle of the flexible
driving-shaft B, which is suitably held in a
vertical socket C, projecting from the casing
D, which incloses the gear-wheel E. A be-
30 veled pinion F is fixed to the end of the spindle
A and meshes with beveled cogs formed on
the gear-wheel E. Straight cogs are also made
round the periphery of the gear-wheel E and
mesh with cogs formed on the pinion G, which
35 revolves on a pin and to which the cutter H
is fastened.

In Fig. 3 I show a vertical pin I, fitted
through a hub formed in the casing D. This
pin abuts against the bottom of the spindle
40 A, forming a "step" or support for it. A set-
screw J is provided for the purpose of hold-
ing the pin I in any desired vertical position,
so that the pinion F may be readily adjusted

to properly mesh with the beveled cogs on the
gear-wheel E.

R is a friction-roller suitably journaled
within a projection L, which may be used as
a handle for the machine. This friction-roller
abuts against the back surface of the gear- 45
wheel E, holding the said gear-wheel in proper
contact with the pinion F. By thus forming
the connection between the flexible driving-
shaft and the cutter the said cutter may be
turned and also moved in a circle horizontally
without swinging the flexible shaft, as the 50
coils of the outer casing of the said shaft will
give sufficiently to permit the said movement,
and consequently my improved cloth-cutting
machine may be manipulated freely around
any form of pattern. 55

What I claim as my invention is—

1. A spindle A, fixed to the driving-shaft
B, supported by an adjustable pin I, and work-
ing in a vertical socket C, and having a be-
veled pinion F fixed to it, in combination with 60
a revoluble gear-wheel E, meshing with the
beveled pinion F, and pinion G, fixed to the
spindle of the cutter H, substantially as and
for the purpose specified.

2. A spindle A, fixed to the driving-shaft 70
B, supported by a vertical socket C, and having
a beveled pinion F fixed to it, and an adjust-
able pin I, forming a step for the spindle A,
in combination with a revoluble gear-wheel
E, meshing with the beveled pinion F, a pin- 75
ion G, fixed to the spindle of the cutter H, and
a friction-roller K, butting against the back
surface of the gear-wheel E opposite to its
connection with the beveled pinion F, sub-
stantially as and for the purpose specified.

Paris, August 28, 1890.

RICHARD SCHOFIELD.

In presence of—

C. M. FOLEY,
E. C. CAPRON.
